UNITED STATES PATENT OFFICE.

HENRY J. WIEGAND, OF MILWAUKEE, WISCONSIN.

REINFORCED-GRID RESISTANCE.

1,071,844.

Specification of Letters Patent. Patented Sept. 2, 1913.

Application filed May 25, 1911, Serial No. 629,497. Renewed February 3, 1913. Serial No. 746,042.

To all whom it may concern:

Be it known that I, HENRY J. WIEGAND, a citizen of the United States, residing at Milwaukee, in the county of Milwaukee and 5 State of Wisconsin, have invented new and useful Improvements in Reinforced-Grid Resistances, of which the following is a full, clear, concise, and exact description, reference being had to the accompanying drawing, forming a part of this specification.

My invention relates to improvements in reinforced grid resistances.

Among the objects of my invention is to provide improved means for attaching a 15 reinforcing strip to a resistance grid.

Other objects and advantages of my invention will hereinafter appear.

In the accompanying drawings I have illustrated one form which my invention 20 may assume in practice. My invention, however is not limited to the form therein shown.

In the views of the drawings:—Figure 1 shows a side elevation of a reinforced grid. 25 Fig. 2 shows a sectional view on line 2—2, Fig. 1. Fig. 3 shows a sectional view on line 3—3, Fig. 1. Fig. 4 shows a detail view of one form of means used to hold the reinforcing strip to the grid.

30 In these drawings I have illustrated a resistance grid 1 of the reflexed type having terminals 2 and reflexed ends 3. These reflexed ends are inclosed in an insulating strip 4, as illustrated in Fig. 2. The strip 35 4 is inclosed in a reinforcing strip 5 having strengthening ribs 6 and constructed as described and claimed in my previously granted Patent No. 982,557 patented Jan'y 24, 1911. In order to provide an improved means 40 for holding the insulating strips and the reinforcing strips in position upon the reflexed ends of the grid as shown in Fig. 1, I preferably employ a suitable rivet or fastener 7 which is passed through openings or slits

45 in the insulating and reinforcing strips as shown in Fig. 2. In a preferred form this fastener is of the T shape illustrated in Fig. 4 and is passed between the arms of a convolution of the grid as shown in Fig. 1 so 50 that its shank is adjacent the inner surface of the curved end of the convolution. After it has been passed through the reinforcing strip and the insulating strip its head is preferably pressed into the reinforcing strip 55 to indent the same and the insulating strip, as shown in Fig. 2 so that the head of the

fastener lies substantially flush with the surface of the reinforcing strip. The bifurcated ends of the rivet are also preferably spread in opposite directions after passing 60 through the strips and are pressed into the surface of the reinforcing strip in the same manner so as to lie substantially flush with the same. Thus it is seen that the strips are securely and snugly held in position on 65 the grid. It is of course to be understood that in applying my invention to practice I may use various other forms of rivets or fasteners, and that the same may be suitably insulated from the grid when passed 70 between the same.

It is to be noted that the rivet or fastener is passed between the arms of one of the convolutions of the grid near its end. In a preferred form the shank of the rivet may be 75 spaced apart from the grid in order to provide air insulation for the same. If desired, however, the fastener may be in electrical contact with the grid since this construction is very simple and rugged. In a 80 preferred form the upper and lower fastening means illustrated in Fig. 1 are offset as shown so that the fastening devices are passed between the ends of successive convolutions. Thus it is seen that the strips 85 upon the ends of the grid are firmly and securely held in place and that the completed grid provided with the strips upon both of its ends is very compact and unitary in construction. 90

While I have in this application described one form which my invention may assume in practice, I do not wish to be limited to the specific construction herein illustrated, but wish to cover all modified forms in 95 which my invention may be incorporated which fall within the scope of the appended claims.

What I claim as new and desire to secure by Letters Patent is as follows:

100

1. The combination with a convoluted resistance unit, of a reinforcing member for the ends of the convolutions thereof provided with means extending through the closed end of a convolution of said unit and 105 secured on the opposite side of said unit to positively retain said reinforcing member on said unit.

2. The combination with a resistance grid, of a U shaped reinforcing strip fitting over 110 an edge thereof and means for clamping said strip upon said grid, said means having

a portion extending through the closed end of one of the convolutions of said grid to positively insure retention of said strip upon said grid.

- 5 3. The combination with a resistance grid, of a U shaped reinforcing strip fitting over an edge thereof and a device extending through opposite sides of said reinforcing strip and through the closed end of one of 10 the convolutions of said grid to tightly

clamp said strip upon said grid and to positively secure the same together.

In witness whereof, I have hereunto subscribed my name in the presence of two witnesses.

HENRY J. WIEGAND.
